ELECTRIC VIBRATOR

James D. Cole, Chicago, Ill., assignor to United Pressed Products Co., Chicago, Ill., a corporation of Illinois

Application December 29, 1958, Serial No. 53,939

Term of patent 14 years

(Cl. D55—1)

Fig. 1 is a top plan view of an electric vibrator showing my new design;

Fig. 2 is a front elevational view thereof;

Fig. 3 is a rear elevational view thereof;

Fig. 4 is a left hand side elevational view thereof; and

Fig. 5 is a right hand side elevational view thereof.

The essential features of my design reside in those portions shown in full lines.

I claim:

The ornamental design for an electric vibrator, substantially as shown and described.
